CLAIM

The ornamental design for a display screen with graphical user interface, as shown and described.

DESCRIPTION

The file of this patent contains at least one drawing executed in color. Copies of this patent with color drawing(s)/photograph(s) will be provided by the Office upon request and payment of the necessary fee.

The single FIGURE is a front view of a display screen with graphical user interface showing an image of our new design.

The outermost broken lines illustrate a display screen and form no part of the claimed design.
